UNITED STATES PATENT OFFICE.

WILLIAM H. SHAFFER, OF CINCINNATI, OHIO.

TRACTION FIRE-ENGINE.

No. 876,404.

Specification of Letters Patent.

Patented Jan. 14, 1908.

Application filed August 22, 1906. Serial No. 321,607.

To all whom it may concern:

Be it known that I, WILLIAM H. SHAFFER, a citizen of the United States, residing at Cincinnati, Ohio, have invented a new and useful Improvement in Traction Fire-Engines, of which the following is a specification.

My invention relates to traction fire engines of the class wherein the same explosive motors are used for both propelling and pumping purposes, and the objects of my improvement are to provide a truck with a series of explosive motors or engines which are directly connected with a corresponding series of force pumps; to provide means for detachably engaging the engines with the traction mechanism of the truck whereby it may be self propelled; to provide a crank shaft with a series of cranks arranged in pairs at equal distances around the shaft for maintaining uniformity in its speed, preventing vibration of the structure and delivering the greater power to the pumps during their heaviest duty; to provide means for maintaining a flow of water through the cylinder jacket when the truck is either in motion or at rest, and to provide simplicity and durability in the construction and assemblage of parts, combined with facility of operation and efficiency of action. These objects are attained in the following described manner, as illustrated in the accompanying drawings, in which:—

Figure 1, is a side elevation with parts removed of a traction fire engine embodying my improvement; Figs. 2 and 3, respective rear and front elevations; Figs. 4 and 5, respective side and rear elevations with parts broken away and parts in section showing the relative position of the pumps and the engines and their intermediate connections; Fig. 6, a plan in section on the line *a—a*, of Fig. 7, and Fig. 7, a vertical section on the line *b—b*, of Fig. 6.

In the drawings, 1 represents the rear axle, 2 the idle traction wheels thereon, 3 the front axle provided with hinged spindles 4 whereon the pilot wheels 5 may turn. Drag bars 6 are yieldingly supported at their rear ends on the rear axle by means of springs 7 and are swiveled at their front ends on bolster frame 8 which is yieldingly supported on the front axle by means of springs 9. The operator's

seat 11 is mounted on the drag bars and hand wheel 12 is accessible therefrom for controlling the usual guiding mechanism for the pilot wheels.

Rails 14 are supported between the drag bars by means of cross bars 15 and bearings 16 for the crank shaft 17 are supported by and between said rails. Said crank shaft is provided with a fly wheel 18 and with a series of preferably six cranks 19 which are arranged in pairs equal distances apart around the shaft.

A series of preferably six, four-cycle explosive engines or motors 21 are supported on bearings 16 by means of columns 22 and the pistons 23 thereof are connected with the respective cranks by connecting rods 24. A similar series of preferably single acting force pumps 25 are secured beneath bearings 16 by means of depending columns 26 with their plungers 27 in alignment with and directly connected to the respective pistons 23 by means of parallel reciprocating rods 28.

A suction chamber common to all the pumps is provided with a vacuum chamber 31 and with a suction opening 32 which may be closed when desired by means of a cap 33 or other suitable means, and a force chamber 30 common to all the pumps is provided with a pressure chamber 34 and with the usual gated discharge openings 35.

The engines are inclosed by a common water jacket 36 which communicates with the suction and force chambers of the pump through the respective main pipes 37 and 38 and with the radiator 39 through the branch pipes 41 and 42. The main pipes are provided with shut off cocks 43 for preventing the flow of water from the jacket when the pumps are empty. An auxiliary pump (not shown) may be provided for maintaining the circulation in the branch pipes when said cocks are closed.

A cam shaft 44 common to all of the engines is driven from the crank shaft and at one-half the speed thereof by means of spur gears 45 and 46. Said cam shaft is provided with a series of cams 47 which serve to intermittently open the respective spring controlled charging and exhaust valves 48 and 49 of the engines by contacting the extensible plungers 51 with the respective

valve stems 52. Any of the ordinary carburetors, exploding devices, throttles or exhaust mufflers (not shown) may be used. Brackets 53 serve to carry the sections 54 of suction hose and a foot board 55 provided with a hand rail 56 is supported on the rear ends of the drag bars for convenience in carrying the firemen.

A friction clutch 57 controlled by means 10 of a foot lever 58 serves to detachably engage an intermediate shaft 59 with the crank shaft. The ordinary variable speed, reversing, and compensating gears are inclosed within a casing 61 and actuated from shaft 15 59 by means of spur gears 62 and hand lever 60 and they in turn transmit the power through the driving shafts 63, bevel gears 64, sprocket wheels 65 and the sprocket chain 66 to the sprocket wheels 67 which 20 are secured on the respective traction wheels and whereby the truck is self propelled.

In operation, the engines connected to one of each pair of cranks are arranged to explode their charges successively during one 25 turn of the crank shaft and the engines connected with the other crank of each pair during the next turn of said shaft, the successive explosion of the charges in all of the 30 engines is thus completed with every two complete turns of the crank shaft. The force of each explosion is exerted directly on the corresponding plunger in forcing the water from the pump. When the suction 35 chamber is closed by means of the removable cap or otherwise, the plungers drive the air from the suction and pulsation chambers and continue to reciprocate in a partial vacuum with little friction. By the engagement of 40 the crank shaft with the propelling mechanism by means of the friction clutch the power of the engines are utilized for self propelling purposes without discontinuing the action of the plungers. Upon arriving at a 45 fire the propelling mechanism may be disconnected from the crank shaft by means of the clutch and water connections made with the pumps quickly and without stopping the engines. By reason of the peculiar 50 arrangement of these multiple single acting engine cylinders each in direct alignment with a single acting pump cylinder, and the pistons of each engine and pump being directly connected together, the greater force 55 of the explosions are not only exerted on the plungers when under full load but when the engine pistons are on their return strokes they carry no load except that of the slight friction of the pump plungers.

60 The arrangement of parts serves to maintain a mechanical balance, uniformity of action, and absence of vibration, and to protect the working parts from excessive wear, in-

suring greater durability and less expense and interruption for repairs. One operator 65 only is needed and the weight and expense of a boiler and its attendant may be dispensed with. A full supply of fuel in the form of hydro-carbon may be carried; there is no danger from sparks; the engines may 70 be started quickly and deliver full power at once and much time may be saved in reaching and in delivering water at a fire after the sounding of the alarm.

Having fully described my improvement, 75 what I claim as my invention and desire to secure by Letters Patent of the United States is:

1. The combination of a truck, a multiple explosive engine thereon, propelling mechanism for the truck, means for detachably engaging the engine therewith, a multiplex force pump in continuous engagement with the engine, a radiator, a water jacket for the engine, pipes in continuous communication 80 therewith from the radiator, and valve controlled branch pipes leading therefrom to the pump.

2. The combination of a truck, a series of explosive engines mounted thereon and provided with a water jacket, a similar series of pumps connected directly with the respective engines and actuated therewith, propelling mechanism for the truck, means for detachably engaging the engines therewith 90 and means for supplying the jacket with water from the pumps.

3. The combination of a multiple explosive engine provided with a water jacket and yieldingly supported on traction wheels, a 100 multiplex force pump supported in alignment therewith and having its plungers connected directly with the pistons of the engine, a radiator, branch connections leading from the pump respectively thereto and to the 105 water jacket, propelling mechanism for the traction wheels, and means for detachably engaging the engine therewith.

4. The combination of a multiple explosive engine supported on traction and pilot 110 wheels, a multiplex force pump secured in alignment thereunder and provided with a water jacket, reciprocating rods connecting the pump plungers directly with the respective pistons of the engine, a crank shaft, 115 connecting rods engaging therewith and actuated by the engine, propelling mechanism engaging with the traction wheels, means for detachably engaging the crank shaft therewith, a radiator, and valved connections 120 thereto with the pump.

5. The combination of a series of bearings yieldingly supported on traction and pilot wheels, a crank shaft journaled therein, a series of four-cycle explosive engines supported on the bearings for actuating the 125

shaft and provided with a common water jacket, a similar series of single acting force pumps depending from the bearings in alignment with the engines, reciprocating rods with a radiator, an open connection thereto with the water jacket, and a valve controlled 16 passage between said connection and the pump.

5 directly connecting the pump plungers with the pistons of the engines, propelling mechanism for the traction wheels, a clutch for detachably engaging the crank shaft there- |
